UNITED STATES PATENT OFFICE.

KARL BARTH, OF ESSEN, GERMANY, ASSIGNOR TO FRIED. KRUPP AKTIENGESELLSCHAFT, OF ESSEN-ON-THE-RUHR, GERMANY.

SELF-DISCHARGING WAGON.

Application filed April 26, 1921. Serial No. 464,690.

To all whom it may concern:

Be it known that I, KARL BARTH, residing at Essen, Germany, a citizen of the German Republic, have invented a certain new and useful Improvement in Self-Discharging Wagons (for which I filed an application in Germany on February 8, 1916), of which the following is a specification.

The present invention relates to a double sided self-discharging wagon, the bottom of which, when the wagon is ready to be loaded, is flat and in which the supporting of the bottom and its guiding when passing over from the loading to the discharging position and vice versa is carried out in a particularly advantageous manner.

The invention will be described with reference to the accompanying drawings which show diagrammatically one embodiment of the subject matter of the invention applied to a self-discharging wagon.

Fig. 1 is a transverse sectional view showing the dumping doors in their operative position.

Fig. 2 is a view similar to that shown in Fig. 1 but with the dumping doors shown in the position they assume in the discharging operation.

The body A of the self-discharging wagon has fixed side walls B. The bottom consists of two doors C and C¹ which are connected to each other by hinges c² in the central longitudinal plane of the body of the wagon and when in the loading position (denoted by I) form a horizontal plane and when in the discharging position (denoted by II) form a saddle. Each of these doors C and C¹ is pivotally connected by swinging supports D and E respectively to the underframe F of the wagon. There is also attached to the door C at a pivot point c³ a connecting rod G, which is pivotally connected at its other end to the underframe F by means of a pin g¹ rigidly connected to it. The connecting rod G lies inside the swinging supports D and E. For the operation of the bottom, which is only necessary when it is returned from position II to position I, any kind of well known arrangement (not shown) may be provided, which may be formed for example by a hand lever keyed on the pin g¹ or by a gearing connected at the point c³ and provided with a locking device which can be thrown out of operation

by the operating mechanism and serves to hold the doors C and C¹ securely in the loading position.

When the wagon is to be discharged, the arrangement for operating the bottom is set in action, whereby the locking device is thrown out of operation. When this takes place the doors C and C¹ in consequence of the pivotal connection with each other and with the underframe F are brought by the connecting rod G and the action of the weight of the load automatically into the discharging position denoted by II. The arrangement and the length of the connecting rod G is such that when the discharging movement takes place, the hinges c² are moved vertically upwards, so that a uniform discharge takes place on both sides and the uniformity of the load on both sides of the underframe is maintained.

I claim—

1. In a self-dumping vehicle comprising a receptacle with a plurality of hingedly connected bottom-forming members and a supporting under frame for said receptacle, a supporting link for each bottom-forming member, said supporting link being pivotally attached to said member and to said frame, and a transverse guide link pivotally connected to one of said bottom-forming members and to said frame and adapted to guide the hinged edges of said bottom-forming members in a substantially vertical line.

2. In a self-dumping vehicle comprising a receptacle with a plurality of hingedly connected bottom-forming members and a supporting under frame for said receptacle, a supporting link for each bottom-forming member, said supporting link being pivotally attached to said member at a point nearer its hinged edge than its outer edge, and to said frame, and a transverse guide link pivotally connected to one of said bottom-forming members and to said frame and adapted to guide the hinged edges of said bottom-forming members in a substantially vertical line.

3. In a self-dumping vehicle, comprising a receptacle with a plurality of hingedly connected bottom-forming members and a supporting under frame for said receptacle, a supporting link for each bottom forming member, said supporting link being pivot-

ally attached to said member and to said frame, whereby on said bottom-forming members assuming the dumping position said links are adapted to swing inwardly past the vertical, and a transverse guide link pivotally connected to one of said bottom forming members and to said frame and

adapted to guide the hinged edges of said bottom-forming members in a substantially vertical line. 10

The foregoing specification signed at Essen, Germany, this 25th day of February, 1921.

KARL BARTH.
